UNITED STATES PATENT OFFICE.

HERBERT J. FRINK, OF HOLYOKE, MASSACHUSETTS.

CALENDERING-MACHINE.

SPECIFICATION forming part of Letters Patent No. 516,646, dated March 20, 1894.

Application filed June 5, 1893. Serial No. 476,633. (No model.)

To all whom it may concern:

Be it known that I, HERBERT J. FRINK, of Holyoke, county of Hampden, State of Massachusetts, have invented an Improvement in 5 Calendering-Machines, of which the following description, in connection with the accompanying drawings, is a specification, like letters and figures on the drawings representing like parts.

10 This invention has for its object the production of a calendering machine wherein the pressure upon either or both ends of the calender rolls may be quickly and easily adjusted, and the mechanism whereby such results are attained is so arranged that the operator has full control thereof at one side of the machine.

In United States Patent No. 282,031, dated July 31, 1883, a paper calendering machine is 20 shown as provided with mechanism for simultaneously raising or depressing both ends of the calender rolls, and also for readily varying the pressure at one end, but in order to also vary the pressure at the other end the 25 mechanism must be operated to change the pressure of the first end mentioned, and then both ends are simultaneously operated until the required pressure at the other end is obtained. This retrograde movement, as it may 30 be called, is objectionable in that it consumes time, during which a considerable amount of material which is being finished in the calendering machine is imperfectly finished, causing more or less damage, and the nicety 35 of adjustment cannot be properly preserved. In other words, one end of the rolls may be adjusted independently, but not so the other end, and by the mechanism hereinafter described either end of the rolls may be adjusted 40 independently or simultaneously.

In accordance therewith my invention consists, in a calendering machine, of independent adjusting shafts to vary the pressure at the ends of the rolls, combined with a separate clutch member for and to operate each 45 of said adjusting shafts respectively, and a common actuator rotatable in either direction, located adjacent to said clutch members and adapted to be thrown into operative engagement with either or both of them to rotate the adjusting shafts singly or simulta-

neously in either direction, substantially as will be described.

Other features of my invention will be hereinafter described and particularly pointed 55 out in the claims.

Figure 1 in front elevation shows a calendering machine, with my invention embodied therein. Fig. 2 is a right hand side view thereof. Fig. 3 is an enlarged detail, partly 60 broken out, of the pressure operating mechanism. Fig. 4 is a detached view of one part of the clutch mechanism, and Figs. 5 and 6 are details to be referred to.

The upright frames A, in which usual cal- 65 ender rolls B have their bearings, tie rods 1 and 2, and the cross-heads A' may be and are of usual construction.

A nut a, having an annular shoulder a' near its lower end, and interiorly threaded, 70 is extended through each cross-head from the lower side, so as to rotate freely therein, and toothed wheels b and b', are rigidly attached to the ends of the respective nuts above the cross-heads. Threaded rods c, c', are extend- 75 ed through the nuts a and are connected at their lower ends to caps c^{2x}, one only being shown, in Fig. 2, which bear upon the journals of the topmost roll of the stack, so that rotation of the threaded nuts will raise or 80 lower the threaded rods c, c', to thereby move the caps c^{2x} correspondingly.

The mechanism thus far described is substantially that shown in the patent referred to.

Upright adjusting shafts b², b³, one at each 85 side of the machine, are supported in suitable bearings a^x, b^x, secured to the frame, pinions c², c³, being secured to said shafts and in mesh with the large gears b and b', respectively, as shown in Fig. 1, while the lower 90 ends of said shafts have secured thereto, as herein shown, bevel gears d and d', engaging other bevel gears d², d³, to be described. An actuating shaft e has its bearings in brackets e^x, forming, as herein shown, a part of the 95 bearings b^x, said shaft being preferably reduced in diameter, as shown in dotted lines Fig. 3, where it enters its bearings to prevent longitudinal movement thereof. The bevel gear d² is fast on the actuating shaft e, but 100 the gear d³ is loose thereon, a key or collar 10, see dotted lines Fig. 3, bearing against its

recessed hub and preventing longitudinal movement. The outer face of said hub is toothed or serrated, as at e' , and said toothed or serrated hub forms a clutch member, 5 whereby it is adapted to be engaged at times by the toothed inner face e^2 of the hub of an actuator, shown as a hand wheel C free to rotate or move longitudinally upon the actuating shaft when in the position shown in Fig. 10 3, the outer face e^3 of the hub being likewise toothed, as shown.

A suitable collar f is secured to the shaft e, and between it and the actuator a flanged hub f' is splined to the actuating shaft, the hub 15 being grooved at f^x , see Fig. 5, to receive the spline s, see dotted lines Fig. 3. The flange f², Figs. 3, 5 and 6, of said hub is preferably rounded, whereby it may be readily grasped and moved by the operator, and the inner 20 face of the hub is toothed, as at e^4 , to form a second clutch member.

As will be evident the two clutch members, the actuator C, and its toothed hub forming connections between said members and the 25 actuator, form a double clutch, and it is obvious that any other suitable clutch may be used, the form of the teeth may be varied, or friction surfaces may be used instead of the teeth. With the parts in the position shown 30 in Figs. 1 and 3, rotation of the hand-wheel or actuator C will produce no effect, but if it is moved along the shaft e to the right, Fig. 3, until the toothed faces e^2 and e^4 engage, and is then rotated, the gears d^3 , d' , will be 35 rotated, and through the adjusting shaft b^3 and intermediate gearing the cap at the left, Fig. 1, will be raised or depressed, to decrease or increase the pressure at that end of the stack of rolls B. To vary the pressure at the 40 other end of the rolls it is only necessary to move the actuator C to the left on the shaft e, whereby the toothed surfaces e' and e^2 are disengaged, continuing the movement until the toothed surfaces e^3 and e^4 are in engagement. Rotation of the actuator will then, 45 through the hub f', rotate the shaft e and gear d^2 fast thereon, and thereby actuate the threaded rod c to raise or lower the cap c^2 at the right hand end of the stack, varying 50 the pressure at that end of the rolls B. If it is desired to vary the pressure at both ends of the rolls simultaneously, the actuator C and the hub f', still in engagement, are moved together to the right, Figs. 1 and 3, till the 55 surfaces e' and e^2 , also engage, whereupon rotation of the actuator C will rotate the gear d^3 directly, and the gear d^2 indirectly through shaft e and hub f'.

From the foregoing it will be seen that the 60 clutch members which operate the adjusting shafts are adapted to be brought into engage-

ment with the actuator by the connections between it and the said separate clutch members, and that the pressure can be immediately increased or decreased at each end of the rolls 65 independently or simultaneously, so that the greatest nicety of adjustment is secured with ease and rapidity.

If the clutch mechanism is in engagement to adjust the ends of the rolls simultaneously, 70 and it is desired to vary the pressure at the right hand end, the hub f' is moved to the left out of engagement with the actuator and the actuating shaft rotated by means of the flange f^2 , thus leaving the actuator C in position to rotate the adjusting shaft b^3 independently, or both actuator and hub, remaining in engagement with each other, may be moved to the left until the faces e' and e^2 , are 80 disengaged, when the actuating shaft and adjusting shaft b^3 can be rotated by the actuator or hand wheel C.

This invention is not restricted to the exact construction and arrangement as herein shown, as the same may be varied or altered 85 without departing from my invention.

I claim—

1. In a calendering machine, independent adjusting shafts to vary the pressure at the ends of the rolls, combined with a separate 90 clutch member for and to operate each of said adjusting shafts respectively, a common actuator rotatable in either direction, located adjacent to said clutch members and adapted to be thrown into operative engagement with 95 either or both of them, to rotate the adjusting shafts singly or simultaneously in either direction, substantially as described.

2. In a calendering machine, caps for the ends of the top roll of the stack, and rotatable adjusting shafts geared to and to raise or lower said caps to vary the pressure on the rolls, combined with an actuator shaft geared to one of said adjusting shafts, a clutch member rotatable with the actuating shaft to operate one adjusting shaft, a separate clutch member geared to and to operate the other adjusting shaft, an actuator supported loosely on the actuating shaft adjacent said clutch members, and rotatable in either direction, 110 said actuator being adapted to be thrown into engagement with either or both members to move the end caps singly or simultaneously in either direction, substantially as described.

In testimony whereof I have signed my 115 name to this specification in the presence of two subscribing witnesses.

HERBERT J. FRINK.
